UNITED STATES PATENT OFFICE.

ALEXANDER GEMMELL AND ALEXANDER BOYD, OF TORONTO, ONTARIO, CANADA.

BOOT AND SHOE.

SPECIFICATION forming part of Letters Patent No. 233,148, dated October 12, 1880.

Application filed August 17, 1880. (No model.)

To all whom it may concern:

Be it known that we, ALEXANDER GEMMELL, manufacturer of boots and shoes, and ALEXANDER BOYD, merchant, both of the city 5 of Toronto, in the county of York, in the Province of Ontario, Canada, have jointly invented a certain new and useful Improvement in Boots and Shoes, of which the following is a specification.

10 The object of the invention is to utilize the movement of the foot for the purpose of ventilating the boot; and it consists in perforating the quarters of the boot on opposite sides thereof over the shank, and inserting in said 15 perforations eyelets of a peculiar construction, as hereinafter more fully set forth.

Figure 1 is a side view of our ventilated boot. Fig. 2 is a cross-section through *a b*; Fig. 3, clip for protecting perforation.

20 In our improved system of ventilation we perforate the quarters *A* on opposite sides, immediately over the shank, thereby admitting air between the arch of the foot and sole *B* of the boot, utilizing the upward and downward 25 movement of the foot for the purpose of drawing in and propelling out the air, a portion being propelled around the foot, the motion of which, as stated, performing the duty of an air-pump.

30 In order to secure the desired effect it is absolutely necessary that the holes should be situated exactly in the position stated—viz., through both sides of the quarters, between the sole and arch of the foot, below the in- 35 step. A fresh current of air is thereby maintained around the foot.

C represents a metallic eyelet of peculiar construction, designed to be inserted in one of the perforations made in the shoe above its shank. The eyelet *C* is provided with a central orifice, *b*, and radial arms *a a*. The central portion of the eyelet is inserted in one of the perforations made in the shoe above its shank, and the ends *c* of the radial arms are passed through perforations made in the shoe, 45 and are then bent inwardly down over the inner face of the leather to secure the metallic eyelet in place. By this construction the perforations in the shoe are prevented from being closed. 50

We are aware that perforations have been heretofore made in the uppers of shoes with valves applied thereto to secure ventilation, and we therefore lay no claim to such construction, our invention being confined to the 55 application to such perforations of the eyelet of the peculiar construction heretofore described.

What we claim as our invention is—

The combination, with a shoe having perforations in its quarters on opposite sides and over the shank, as set forth, of the eyelets *C*, each having a central orifice, *b*, and radial arms *a*, the ends *c* of which are adapted to be inserted in perforations in the shoe and bent inwardly 65 along the inner face of the leather, substantially as described.

ALX. GEMMELL.
ALEXANDER BOYD.
